Primary Examiner — Karen S Acker*Assistant Examiner* — Wendy Arminio(74) *Attorney, Agent, or Firm* — Suzanne Kikel, Patent Agent(57) **CLAIM**

The ornamental design for a reusable sealing bottle cap assembly, as shown and described.

DESCRIPTION

FIG. 1 is a perspective view of a reusable sealing bottle cap assembly in an inoperative position.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof.

FIG. 7 is a rear elevational view thereof.

FIG. 8 is a bottom perspective view thereof; and,

FIG. 9 is a perspective view of the reusable sealing bottle cap assembly in an operative position on a bottle.

The broken lines in FIG. 9 depict environment that forms no part of the claimed design.

1 Claim, 3 Drawing Sheets(56)
